C. J. PAULSON,

RIBBON SHIFT FOR TYPE WRITERS.

APPLICATION FILED MAY 18, 1906

2 SHEETS—SHEET 2.

UNITED STATES PATENT OFFICE.

CHARLES J. PAULSON, OF BROOKLYN, NEW YORK.

RIBBON-SHIFT FOR TYPE-WRITERS.

No. 872,447.

Specification of Letters Patent.

Patented Dec. 3, 1907.

Application filed May 18, 1906. Serial No. 317,540.

To all whom it may concern:

Be it known that I, CHARLES J. PAULSON, a subject of the King of Sweden, residing in Brooklyn, in the county of Kings and State 5 of New York, have invented certain new and useful Improvements in Ribbon-Shift for Type-Writers, of which the following is a specification.

This invention relates to ribbon supporting mechanism for typewriters, and is particularly designed for use in connection with what are termed "sight typewriters", wherein the place on the platen that is being struck by the typebars is plainly visible to the operator. In such machines it is customary to shift the ribbon at each stroke of the typebar, over the printing place to be engaged by the type, and thereupon the ribbon is immediately returned to its former position to enable the character printed to be plainly visible.

The object of the present invention is to provide means for so shifting the ribbon at each stroke from the universal bar or otherwise, and to further provide means whereby the position of the ribbon at such printing stroke may be varied, so that it may be engaged by the typebar at various positions transversely across its width; or it may even be shifted beyond such position when it is desired to operate without the ribbon, as when forming a matrix for mimeograph work or the like.

An additional object of the invention is to provide means for varying the position to which the ribbon is shifted at each printing stroke, at the same time that the carriage or platen member is shifted to accommodate for two or more type on each type bar; as is usually the construction to provide upper and lower case letters for each type bar, and also sometimes an additional character on the type bar.

In the accompanying drawings representing one embodiment of my invention, Figure 1 is a side elevation of certain portions of a typewriter having my invention applied thereto. Fig. 2 is a perspective view showing certain portions of the operating mechanism. Fig. 3 is a vertical section through certain parts shown in Fig. 2. Fig. 4 shows separately the flexible shaft for controlling the shaft of the ribbon guide; and Figs. 5, 6 and 7 show the cam portion of the flexible shaft in its different operative positions.

The typewriter is designated generally by

T and the ribbon R is carried by suitable spools S, only one of which is shown. The platen is indicated by P, and the ribbon is supported to be brought adjacent the platen 60 to engage by the typebars B when the latter are depressed in the usual manner.

Mounted on suitable standards 11 and 12 is a supporting rod 13, on which is secured a supporting arm 14. Adjacent the rod 13 is 65 a flexible shaft 16 rotatably supported at one end only, in a bracket 17 fast on the standard 12. This flexible shaft extends substantially parallel with the rod 13, and is rotatable from a shaft 18 by means of bevel gears 19 and 20 on the respective members; shaft 18 being controlled by an indicating arm 21, that can be shifted to the three positions, such as "red, black and plain", as indicated on the front plate 22.

A lever 23 is pivoted at its intermediate part in the lower portion of the supporting arm 14, and has one extremity secured to a collar 35 loose on the free end of the flexible shaft 16. The other projecting end of the 70 lever 23 is connected with the universal bar 15 by a link 24. When the universal bar is depressed, the link will serve to rock the lever 23. A ribbon guide 25 is supported to slide on an arm 28 extending transversely 75 from the arm 14. This ribbon guide is moved in one direction by a lever 26 pivoted on the supporting arm 14. A spring 27 is connected between the lever 26 and the guide 25. When the lever is rocked to advance the 80 guide, this spring will be extended, by reason of the angular divergence of the lever and guide. Therefore the reaction of this spring will return the guide and arm 26 to their former positions. A second lever 29 is pivoted 85 in an upright arm 9 and engages a portion of the lever 26 by its intermediate portion. The lever 29 has its inclined end portion engaged by a cam surface 30 on the flexible shaft 16, whereby the rotation of the shaft will rock 90 the lever 29, as indicated in Figs. 5, 6 and 7.

The flexible shaft 16 is retained in three different positions, corresponding to the indications on the plate 22, by means of a spring clip 31 fast on the shaft, that engages flat 105 surfaces 32, 33 and 34, formed on a collar 35 fast to the lever 23.

Instead of an arm 29 being pivoted on a stationary member, it may be pivoted on an arm 9 that serves to shift the platen when it 110 is desired to print another case letter formed on the type bar B. The arm 9 is shown in

Fig. 1 as pivoted at 7 and has a bent arm 8 operably connected with a key lever 6. By any suitable means, not shown, the operation of the key lever rocking the arm 9 will serve 5 to shift the platen for the said purpose.

The operation of the device is as follows: With the indicator 21 in the position shown in Fig. 2, the flexible shaft will have its cam surface 30 normally in the position indicated 10 in Fig. 7. Now, upon the movement of the universal bar 15 depressing the link 24, the lever 23 will swing downwards. This lever being pivoted at its middle portion, will swing upward the free end of the flexible 15 shaft 16. The latter will elevate the lever 29, that will swing the lever 26 to advance the ribbon guide 25. But in this position, the ribbon guide will only be advanced a minimum distance, and the ribbon will not 20 be brought to the printing place of the type bar B. Upon shifting the arm 21 to the "black" position, the cam 30 will be swung to the position indicated in Fig. 6. From this it will be seen that in its normal position 25 the lever 29 will be elevated from the position shown in full lines in Fig. 3 to that indicated in broken lines; and the same follows for the lever 26, it remaining in the broken line position. Upon now operating the universal bar, since the lever 23 swings through 30 the same length of arc as in the previous instance, the lever 26 will be moved through the same distance, but through a different path, its initial position being advanced from 35 that in the previous instance. This will cause the ribbon to be shifted farther across the platen at each operation of the universal bar, and this will serve to bring the portion 37 of the ribbon into the striking point of the 40 type bar, causing it to print black. Upon shifting the indicator arm 21 to the position of "red", the cam 30 will be shifted to the position indicated in Fig. 5 and the normal position of the levers 29 and 26 will be further elevated, and the ribbon guide, upon the 45 next operation of universal bar will be shifted still further. This will permit the red portion 36 of the ribbon to be brought to the striking place of the type bar. The spring 50 31 engaging the flat faces on the end portion of the flexible shaft 16 will serve to retain the shaft from rotating away from such axial position, yet will permit elevation of the shaft by the lever 23 at each operation of the universal bar. But, when the arm 9 is rocked 55 to shift the platen for upper case, or other additional character carried by the type bar, the lever 29 will be moved rearward as indicated in Fig. 2. This will cause its inclined 60 end portion engaging the cam 30, to be elevated by the cam, and slightly rock the lever 26. The latter movement will obviously advance the ribbon guide 25. This operation will have the same effect of advancing the 65 ribbon guide in whichever of the three posi-

tions the guide member is adjusted to operate by means of the controlling arm 21. That is, to whichever of the three positions the ribbon guide would be shifted by the operation of the universal bar, it will be shifted 70 at such operation a short distance, and thereby the other character on the type bar will print, either red, black or plain according to the adjustment of the controlling arm.

Having thus described my invention, I 75 claim:

1. In a typewriter, the combination of a supporting member, a ribbon guide arranged to reciprocate on the supporting member toward and from the printing position, a flexible shaft supported to oscillate, means for causing the transverse reciprocation of the flexible shaft to reciprocate the ribbon guide, said means being organized to vary the positions to which the ribbon is carried by the 85 ribbon guide upon rotative adjustment of the shaft.

2. In a typewriter, the combination of a supporting member, a ribbon guide arranged to reciprocate on the supporting member toward and from the printing position, a flexible shaft supported to oscillate, means for causing the transverse reciprocation of the flexible shaft to reciprocate the ribbon guide, said means being organized to vary the positions to which the ribbon is carried by the 95 ribbon guide upon rotative engagement of the shaft, and means for effecting the transverse reciprocation of the flexible shaft from the universal bar.

3. In a typewriter, the combination of a supporting member, a ribbon guide arranged to reciprocate on the supporting member toward and from the printing position, a flexible shaft supported to oscillate, means for 105 causing the transverse reciprocation of the flexible shaft to reciprocate the ribbon guide, said means being organized to vary the positions to which the ribbon is carried by the ribbon guide upon rotative engagement of 110 the shaft, means for effecting the transverse reciprocation of the flexible shaft from the universal bar, and means for rotatively adjusting the flexible shaft.

4. In a typewriter, the combination of a 115 supporting member, a ribbon guide arranged to reciprocate on the supporting member toward and from a printing position, a flexible shaft, a lever pivotally supported and arranged to move said shaft transversely when 120 rocked, means for causing the bending of the flexible shaft by said lever to reciprocate the ribbon guide, said means including means to vary the movement of the ribbon guide by the movement of the flexible shaft on its 125 axis.

5. In a typewriter, the combination of a supporting member, a ribbon guide arranged to reciprocate on the supporting member toward and from a printing position, a flexible 130

shaft, a lever pivotally supported and arranged to move said shaft transversely when rocked, means for causing the bending of the flexible shaft by said lever to reciprocate the 5 ribbon guide, said means including means to vary the movement of the ribbon guide by the movement of the flexible shaft on its axis, means for swinging the flexible shaft on its axis to different positions, and means for 10 retaining the shaft in such adjusted positions.

6. In a typewriter, the combination of a supporting member, a ribbon guide slidably carried on the supporting member to move toward and from a printing position, a lever 15 pivoted on the supporting member and operated from a universal bar, a flexible shaft supported to rotate, said shaft being connected with said lever whereby the swinging of the lever will bend the flexible shaft from 20 its axial line, a second lever, the flexible shaft having a cam surface where engaged by said lever, means for causing the swinging of the second lever by the cam surface of the shaft to oscillate the ribbon guide, said cam 25 portion of the flexible shaft, and its engaging lever being organized to shift the normal position of the lever by the rotary adjustment of the flexible shaft.

7. In a typewriter, the combination of a 30 supporting member, a ribbon guide slidably carried on the supporting member to move toward and from a printing position, a lever pivoted on the supporting member and operated from a universal bar, a flexible shaft 35 supported to rotate, said shaft being connected with said lever whereby the swinging of the lever will bend the flexible shaft from its axial line, a second lever, the flexible shaft having a cam surface engaged by said second 40 lever, means for causing the swinging of the said second lever by the cam surface of the shaft to oscillate the ribbon guide, said cam portion of the flexible shaft, and the second 45 lever being organized to shift the normal position of the second lever by the rotary adjustment of the flexible shaft, means for swinging the flexible shaft, and means for retaining the flexible shaft in such adjusted positions.

50 8. In a typewriter, the combination of a supporting member, a ribbon guide slidably carried on the supporting member to move toward and from a printing position, a lever pivoted on the supporting member and operated from a universal bar, a flexible shaft 55 supported to rotate, said shaft being connected with said lever whereby the swinging of the lever will bend the flexible shaft from its axial line, a second lever, the flexible shaft 60 having a cam surface engaged by said second lever, a third lever engaging said second lever and also engaging the ribbon guide whereby the swinging of the second lever by the cam surface of the shaft will oscillate the ribbon 65 guide, said cam portion of the flexible shaft 70

and its said engaging lever being organized to shift the normal position of the lever by the rotary adjustment of the flexible shaft.

9. In a typewriter, the combination of a supporting member, a ribbon guide slidably 70 carried on the supporting member to move toward and from a printing position, a lever pivoted on the supporting member and operated from a universal bar, a flexible shaft supported to rotate, said shaft being connected with said lever whereby the swinging of the lever will bend the flexible shaft from its axial line, a second lever, the flexible shaft having a cam surface where engaged by said second lever, a third lever engaging said second lever and also engaging the ribbon guide whereby the swinging of the second lever by the cam surface of the shaft will oscillate the ribbon guide, said cam portion of the flexible shaft 75 and its engaging lever being organized to shift the normal position of the lever by the rotary adjustment of the flexible shaft, means for effecting such adjustment of the flexible shaft, and means for retaining the flexible shaft in such adjusted positions. 80

10. In a typewriter, the combination of a supporting member, a ribbon guide slidably carried on the supporting member to move toward and from a printing position, a lever pivoted on the supporting member and operated from a universal bar, a flexible shaft supported to rotate, said shaft being connected with said lever whereby the swinging of the lever will bend the flexible shaft from 95 its axial line, a second lever, the flexible shaft having a cam surface where engaged by the second lever, a third lever engaging said second lever and also engaging the ribbon guide whereby the swinging of the second lever by the cam surface of the shaft will oscillate the 100 ribbon guide, said cam portion of the flexible shaft and its engaging lever being organized to shift the normal position of the lever by the rotary adjustment of the flexible shaft, and resilient means arranged to retain said 105 levers in engagement with said members. 110

11. In a typewriter, the combination of a supporting member, a ribbon guide slidably carried on the supporting member to move toward and from a printing position, a lever 115 pivoted on the supporting member and operated from a universal bar, a flexible shaft supported to rotate, said shaft being connected with said lever whereby the swinging of the lever will bend the flexible shaft from 120 its axial line, a second lever, the flexible shaft having a cam surface where engaged by said second lever, a third lever engaging said latter lever and also engaging the ribbon guide whereby the swinging of the second lever by the cam surface will oscillate the ribbon 125 guide, said cam portion of the flexible shaft and its engaging lever being organized to shift the normal position of the second lever by the rotary adjustment of the flexible 130.

shaft, means for effecting such adjustment of the flexible shaft, means for retaining the flexible shaft in adjusted positions to which it is swung by said means, and an indicator 5 for indicating the adjusted positions of the flexible shaft.

12. In a typewriter, the combination of a supporting member, a ribbon guide member carried on said member to be shifted thereon 10 to and from the printing position, means for reciprocating the ribbon guide to and from the printing position from the movement of a universal bar, a controlling member arranged to be shifted to a plurality of positions, the 15 controlling member and the mechanism operating the ribbon guide being organized whereby the ribbon guide will be shifted to different positions by the universal bar according to the position of the controlling 20 member, a reciprocatable member, and means for causing the shifting of said member to vary the said path of movement of the guide member to change the printing position 25 of the ribbon for such adjustment.
13. In a typewriter, the combination of a supporting member, a ribbon guide slidably carried on the supporting member to move toward and from a printing position, a lever pivoted on the supporting member and operated from a universal bar, a flexible shaft supported to rotate, said shaft being connected with said lever whereby the swinging 30 of the lever will bend the flexible shaft from its axial line, a second lever pivoted on a movable member, the flexible shaft having a cam surface engaged by said second lever, a 35 third lever engaging said second lever, and also engaging the ribbon guide whereby the swinging of the second lever by the cam surface of the shaft will oscillate the ribbon guide, said cam portion of the flexible shaft and its said engaging lever being organized 40 to shift the normal position of the lever by the rotary adjustment of the flexible shaft, and means for shifting the movable member to shift the position of the second lever and vary the paths of movement of the ribbon 45 guide for the several adjustments.

14. In a typewriter, the combination of a supporting member, a ribbon guide slidably carried on the supporting member to move 50 toward and from a printing position, a lever pivoted on the supporting member and operated from a universal bar, a flexible shaft supported to rotate, said shaft being connected with said lever whereby the swinging 55 of the lever will bend the flexible shaft from its axial line, a second lever pivoted on a movable member, the flexible shaft having a cam surface engaged by said second lever, a third lever engaging said second lever, and 60 also engaging the ribbon guide whereby the swinging of the second lever by the cam surface of the shaft will oscillate the ribbon guide, said cam portion of the flexible shaft and its said engaging lever being organized 65 to shift the normal position of the lever by the rotary adjustment of the flexible shaft, and means for shifting the movable member to shift the position of the second lever and vary the paths of movement of the ribbon 70 guide for the several adjustments.

Signed at Nos. 9 to 15 Murray street, New York, N. Y., this 15th day of May, 1906.
